SLIDING DOOR PULL

John F. Henshaw, San Francisco, Calif., assignor to
Schlage Lock Company, a corporation

Filed Sept. 14, 1959, Ser. No. 57,547

Term of patent 14 years

(Cl. D10—8)

FIG_1

FIG_6

FIG_2

FIG_3

FIG_4

FIG_5

Fig. 1 is a perspective view of a sliding door pull showing my new design;

Fig. 2 is a top plan view of the pull;

Fig. 3 is a side elevation;

Fig. 4 is a front elevation;

Fig. 5 is a side elevation of the side opposite that shown in Fig. 3; and

Fig. 6 is cross section as taken along lines VI—VI in Fig. 4.

I claim:

The ornamental design for a sliding door pull, as shown.
